CABLE-BRAKING APPARATUS

Arthur Stanley Avis, Ashford, England, assignor to Vickers-Armstrongs (Aircraft) Limited, London, England, a British company

Filed July 19, 1961, Ser. No. 125,210

Claims priority, application Great Britain July 21, 1960

7 Claims. (Cl. 242—107.3)

This invention has reference to apparatus for use in lowering a load by means of a cable payed out from a winch or the like, the object being to provide means whereby the speed of lowering may be controlled at a desired rate, and for the rewinding of the cable after use. A further object is to provide means whereby a load may be partially supported when, during the operation of raising the load manually, the lifting effort is momentarily relaxed.

Apparatus for the purpose stated comprises a helically grooved drum upon which the cable connection with the load may be wound, said drum being adapted to be driven for rewinding the cable by a spring motor which is energised by the reverse rotation of its driving element when the load is payed out, and a friction brake unit which is automatically clutched to a stationary part of the apparatus when the load is payed out and released when the cable is rewound. The apparatus is preferably enclosed in a casing having an aperture for passage of the cable therethrough to and from the drum, the drum being splined upon the driving element of the spring motor for axial movement in the casing so that the point at which the cable enters or leaves the helical groove of the drum remains opposite said aperture at all times.

The manner in which the invention may be carried into effect is hereinafter described in greater detail with reference to the accompanying drawings. In said drawings FIG. 1 is a perspective view of part of the interior of a stowage compartment e.g. of an aeroplane, illustrating the use of the supporting and lowering apparatus provided by the present invention for the suspension of a load. FIG. 2 is a partly sectional elevation of the supporting and lowering apparatus shown separately, and FIGS. 3 and 4 are transverse sections taken respectively on the lines III—III, and IV—IV, of FIG. 2.

It may be seen from FIG. 1 that the invention is concerned with the provision of means for supporting a load A within the stowage compartment of which the ceiling and one wall are respectively indicated at B and C. Such means as provided by the invention takes the form in this embodiment of the apparatus, indicated in FIG. 1 generally by the reference letter D, which is illustrated in detail in FIGS. 2 to 4. Cables for the suspension of the load A at its opposite ends are payed out from the apparatus D, one such cable extending vertically downwards and the other being passed over a guide-pulley E.

Referring now to FIGS. 2 to 4 of the drawings, it will be seen that the apparatus D is enclosed in a casing which is conveniently fashioned in two cylindrical complementary sections 101 and 102 having abutting flanges 1011 and 1021 which are bolted together at 103. Mounted rotatably within the inner cylindrical bore provided by the combined inner walls of the two casing sections 101, 102 is a drum 11 having an external peripheral helical groove 111 in which are laid the two cables previously referred to and here designated by the reference numerals 12 and 13. At one end the cables are attached to the drum and their other ends emerge from the casing through holes of which one is shown at 131. In order that the point at which each cable leaves the drum groove 111 may remain opposite

2

the relative aperture at all times, the casing section 101 is provided with a peg 14 which projects inwardly to engage the groove 111, in such manner that as the drum 11 is rotated by the paying-out or winding in of the cables it is constrained by the cooperation of the peg with the groove to move axially within the casing.

A disc 15 is splined within the drum 11 and arranged to lie flush against the adjacent face of a plate 16 which is provided with an axial boss which is rotatably mounted upon a stud journal 17 mounted on the inner end-wall of the casing section 101. An enlarged part 171 of the stud 17 is bored to fit upon a hub 1012 which projects axially inward from the casing section 101, and a hexagonal-section plug 18 is received in conformably shaped sockets in the stud 17 and hub 1012 to prevent rotation of the former relative to the latter. Mounted upon the disc 15 in equiangular spacing about its axis are a plurality of screws 19 each of which carries two aligned rotatable spools 20, 21, and each such spool has wound thereon a flat torsion spring 22 the end of which is anchored at 23 to one of the faces of the polygonal-section part 171 of the stud 17. The arrangement is such that when the cables 12, 13 are payed out to lower the load, the disc 15 rotates with the drum 11 in relation to the member 171 and the several springs 22 are unwound from their spools and wound in the opposite sense in superposed relation upon the member 171. When the load is removed from the cables at the end of the lowering operation, the energy stored in the springs 22 drives the disc 15, causing the drum 11 to be rotated in the reverse direction, and as the springs 22 are re-wound upon their spools the cables 12, 13 are re-wound in the groove 111 of the drum 11.

The lowering operation is controlled, and a load is partially supported, by a friction brake unit which is applied to the drum. A single clutch plate 24, splined at its periphery within the drum 11 so as to be driven by the rotation thereof, is mounted between two stationary friction elements 25 and 26 which are respectively carried by the plate 16 and an annular member 27 which is attached by screws 271 to the face of said plate 16 remote from the disc 15. A pressure plate 28 splined on the member 27 is arranged to impart pressure through an assembly of coiled springs 29 to the friction element 26 so that the clutch plate 24 and the two friction elements 25, 26 are compressed and, through the driving connection between the clutch plate 24 and the drum 11, the rotation of the latter is retarded. The outer ends of the springs 29 are received in a recessed annulus 30 which is slidable on the member 27 and is adapted to be adjusted thereon by a nut 31 which is threaded on an axial extension 272, of the member 27, rotation of said nut being effective to vary the pressure of all the springs 29 collectively.

The member 27 is counter-bored throughout part of its axial length to receive a spigot 32 which is attached to the casing section 102. The combined bores of the member 27 and said spigot 32 are used to house a rectangular close wound helical spring 33, hereinafter referred to as the "locking spring," which is an interference fit in said bores and the end of which is anchored at 331 in an internal sleeve 34 which is rotatable in the casing section 102, the arrangement being such that on rotation of the clutch plate 24 with the drum 11 when the cables 12, 13 are payed out, a braking force is applied to the clutch plate by the fact that the member 27 is clutched thereto by its rotation against the lay of the locking spring 33. When the clutch plate 24 is rotated in the opposite direction the locking action of the locking spring 33 is neutralised by the clutch assembly rotating with the lay thereof.

The sleeve 34 may be partially rotated with the aid

of a tommy-bar passed through the holes 341, in the direction of the lay of the spring 33 to permit the easy withdrawal of the cables, if required, by freeing the annulus 27 from the spring 33 temporarily.

What I claim as my invention and desire to secure by Letters Patent is:

1. Apparatus, capable of use for paying-out and re-winding load-connected cables, comprising: a helically-grooved drum, arranged for rotation and for limited translation in directions along its axis of rotation; at least one cable laying in the drum's helical groove thereby defining a helical cable winding about the drum, one end of the cable being anchored to the drum, the other end of the cable having means for its connection to a load; control means; friction braking means automatically controlled, by said control means, for retarding the rotation of the drum when rotating in a direction to pay-out said cable, and for not retarding the drum's rotation when rotating in a direction to rewind said cable about the drum; spring motor means, including a driving element coupled with the drum, for rotating the drum in a direction to rewind said cable, said driving element energizing said spring motor means as the drum is rotating in a direction to pay-out the cable; and, a casing, having at least one aperture therethrough, enclosing at least the drum, the aperture allowing passage of the cable to and from the drum, said casing including a fixed abutment arranged with the drum's groove to effect translation along the axis of rotation of the drum as the drum rotates whereby the point on said groove at which the cable is payed out, or rewound, always remains opposite said aperture.

2. Apparatus as defined by claim 1, wherein the spring motor means comprises a disc-like driving element splined in the drum for rotation therewith, an axially disposed fixed member mounted on the disc-like driving element, a plurality of spools mounted on said disc-like element, each spool having a torsion spring wound thereon with the end of the spring anchored to the axially disposed fixed member, the arrangement being such that when the cable is payed out the rotation of the disc-like element is effective to unwind the springs from the spools and to wind them upon said fixed member in the opposite sense,

the energy thus stored in said springs serving to drive the disc-like element and drum in the reversed direction when the load is removed.

3. Apparatus as defined by claim 2, wherein the spools are disposed in equiangular spacing about the axis of the disc-like element and so arranged that the springs are re-wound upon the fixed member in superposed relation.

4. Apparatus as defined by claim 1, wherein the friction braking means comprises a clutch plate fastened to the drum, a support member arranged within the casing, two friction elements mounted on the support member, the clutch plate being situated between the two friction elements, and an assembly of compression springs mounted on the support member and arranged for compressing the friction elements against said clutch plate.

5. Apparatus as defined by claim 4, wherein said support is an annulus mounted within the casing co-axially with the drum, and wherein the compression springs are disposed between two pressure plates splined upon an outer surface of said annulus, one of said plates being adjustable on the annulus in an axial direction for variation of the effective pressure of the springs on the friction elements.

6. Apparatus as defined by claim 1, wherein the automatic control means comprises a close wound rectangular-section helical locking spring so coupled with the friction braking means whereby rotation of the drum in the cable pay-out direction is retarded by the lay of the wound spring relative to the braking means and rotation of drum in the rewind direction is not retarded by the lay of the wound spring relative to the braking means.

7. Apparatus as defined by claim 6, wherein said automatic control means comprises additional means for temporarily uncoupling said locking spring and braking means.
